UNITED STATES PATENT OFFICE.

LOUIS G. RÉGNIER, OF NEW YORK, N. Y.

AUTOMAGNETIC BOWLING ALLEY.

Application filed August 27, 1921. Serial No. 495,919.

To all whom it may concern:

Be it known that I, LOUIS G. RÉGNIER, a citizen of the United States, and a resident of the city of New York, borough of the Bronx, in the county of Bronx and State of New York, having invented a new and Improved Automagnetic Bowling Alley, of which the following is a description.

The general object of my invention is to provide a bowling alley having automatic means for carrying the pins out of normal position in the alley when the pins are struck and having means whereby the pins may be mechanically set up.

15 The manner in which the above and other objects as will appear are attained will be readily understood from the following description of a practical embodiment of the invention.

20 Reference is to be had to the accompanying drawings forming a part of this specification, and in which—

Figure 1 is a plan view of a portion of a bowling alley constructed in accordance with 25 my invention;

Figure 2 is a side elevation thereof;

Figure 3 is a longitudinal vertical section on the line 3—3, Figure 1, showing certain 30 of the pins automatically raised and the resetting head in the raised position;

Figure 4 is a view similar to Figure 3 but with the resetting head lowered and the pins in set-up position;

Figure 5 is a rear end view of the bowling 35 alley; and

Figure 6 is a transverse vertical section on the line 6—6, Figure 2.

In carrying out my invention in accordance with the illustrated example, a suitable 40 base 10 is provided having the usual raised ball run and pin table. The pins 11 have in practice metallic elements 12 at the bottom adapted to be influenced by magnets 13 or equivalent pin-holding means, there being 45 one magnet in the base structure and pin platform beneath each pin.

The pins are secured at their upper ends to cords, wires, or like flexible elements 14 that run upwardly to sheaves 15 on a structure 16 rigid with the base, said flexible elements having weights 17 suspended thereon and operating in vertical weight pockets 18. At the rear of the alley is a suitable back stop 19.

55 The alley is adapted to employ the well-

known bowling balls. These when rolled against the pins are run to a sloping transverse gutter 20 with which is a communicating gutter 20^a running rearwardly, the rear end of the bowling alley having a hole 20^b 60 through which the balls may pass to an elevator 21, the bottom 21^a of which is inclined longitudinally.

The elevator 21 is adapted to be manually raised by a hoist rope 23 running over a pulley 24 on the elevator guide frame or fixed structure 22, said rope running downwardly about a sheave 25 on the base 10 at the under side and forwardly to any convenient point to be pulled by an attendant or player. Or, said ropes may be otherwise run for their convenient operation. When the elevator is raised the balls will run from the inclined bottom thereof to a trackway 37 70 running in practice to the front of the alley. 75

Above the pins 11 is a resetting head 26. Vertical holes or pockets 27 in the resetting head 26 are adapted to accommodate a pin 11 when the latter is raised by the weights 17. Said head 26 moves between suitable 80 vertical guides 26^a forming a part of the fixed alley structure.

Resilient elements 28, usually of wire, are provided on the resetting head 26 at the top and are positioned to extend across the 85 pockets 27. Said elements 28 serve to insure contact between the pins and magnets when the resetting head is lowered. The elements 28 also serve as cushions or shock absorbers in receiving the impact of the pins when the latter are raised. Each element 28 presents an eye through which a flexible element 14 runs to and from a sheave 15, the opposite end of the guide from the eye being suitably secured to the top of the head 90 95 26 as by screws 29.

To the head 26 is secured cords, wires, or other flexible elements 30, which run rearwardly to and over pulleys 31 and downwardly to a counter-balance weight 32 normally tending to maintain the resetting head 26 in the raised position. For relieving the head 26 of the pull of the weight 32 to thereby permit the resetting head to lower, ropes 33 are secured to the weight 32 and run upwardly and about sheaves 34, thence downwardly, preferably through vertical guide tubes 35 in the weight 32, and about sheaves 36 on the base 10 and forwardly at the under side of the base to a convenient 100

point to be pulled by an attendant or player. Obviously, the ropes 33 may run to any point for their convenient pulling.

In order to prevent undue displacement of the pins 11, I provide guards 38 in the form of elongated bars disposed transversely in a vertical plane between the respective transverse rows of pins, said guards 38 including hanger arms 39 which extend slidably 10 through keepers 40 on the resetting head 26 to have vertical movement relatively to said head. The downward movement of the guards 38 relatively to the head 26 is limited by collars, 41, nuts, or the like on the hangers 15 39 at their upper ends.

With the above described construction when balls are rolled against the pins 11, the impact will overcome the influence of the magnet 13 so that the struck pins will 20 be free to respond to a pull of the weights 17 so that the said pins will be caused to rise into the openings 27 of head 26. When it is desired to restore the pins the head 26 is lowered by exerting a pull on the ropes 25 33 for raising the weight 32. In the lowering of the head 26 the guards 38 will pass between the pins and strike the pin platform but the slideable connection between the hangers 29 and head 26 will permit said 30 head to continue its downward movement for the placing of the pins 11 directly above the magnets 13. The head 26 in being raised will move relatively to the guards 38.

I would state in conclusion that while the 35 illustrated example constitutes a practical embodiment of my invention, I do not limit myself strictly to the exact details herein illustrated, since, manifestly, the same can be considerably varied without departure from 40 the spirit of the invention as defined in the appended claims.

Having thus described my invention, I claim:

1. A bowling alley, pins therein, means to 45 hold the pins in position for a play, weighted flexible elements secured to said pins and tending to raise the latter, a resetting head

provided with slideable guides adapted to receive the pins when raised, said guides guiding said pins, flexible elements suspending the resetting head, a suspended weight to which said last-mentioned elements are secured, said weight normally maintaining the resetting head raised, and manually operative means to raise said weight and permit said head to lower.

2. A bowling alley, pins therein, means tending to raise the pins from set position, a movable head adapted to receive said pins when raised, means to hold the pins in the set position against the tendency to rise until the pins are struck, and guards positioned in planes adjacent to the vertical planes of the pins and slideably carried by said head to prevent undue displacement of the pins.

3. A bowling alley, pins therein, means to hold the pins in set position until struck, means secured to the individual pins to raise the same when released from said holding means, a resetting head above the set position of the pins and movable downwardly for the resetting of the pins, and guards disposed in vertical planes alternating with the vertical planes of the rows of pins, said guards being slideably connected 75 with the said resetting head for vertical movement relatively to the head when the latter is lowered.

4. A bowling alley including pins, means for holding the respective pins in their set 80 positions, means to raise the pins when bowled over, a resetting head for the pins, said head being normally in a position above the pins and adapted to be lowered, and resilient means carried by said head in positions to engage the pins when the latter are raised, said resilient means being adapted to press the pins to positions above the holding means with the lowering of the resetting head; together with pin guard means carried by said head and movable relatively to 85 said head.

LOUIS G. RÉGNIER.
